UNITED STATES PATENT OFFICE.

AUGUST FREDERICK KAMMER, OF CLIFTON, NEW YORK, ASSIGNOR TO CARR-LOWREY
GLASS CO., OF BALTIMORE, MARYLAND.

DISPENSING-BOTTLE.

1,316,723.

Specification of Letters Patent. Patented Sept. 23, 1919.

Application filed July 11, 1916. Serial No. 108,638.

To all whom it may concern:

Be it known that I, AUGUST FREDERICK KAMMER, a citizen of the United States, residing at 55 Simonson avenue, Clifton, in the county of Richmond and State of New York, have invented a new and useful Dispensing-Bottle, of which the following is a specification.

This invention relates to dispensing bottles of that type used for sprinkling talcum powder and like substances.

Heretofore it has been the practice to provide bottles with metal caps in which have been formed small perforations. Because of the rapidly increasing cost of metal, however, the use of metal caps has become objectionable and, objection has also been made to the use of metal caps by reason of the fact that the powder in the container often acts chemically upon the metal with the result that both the metal and the powder within the container become discolored.

One of the objects of the present invention is to provide a dispensing bottle in which no metal is used but which, instead, has a combined sprinkler top and packing formed of cork or other suitable material of a like nature and which sprinkler cap constitutes a receiver for a stopper which serves to close the perforations in the sprinkler cap and also to provide an artistic finish to the container.

A further object is to cheapen the cost of producing bottles of this type by substituting a much cheaper material for the metal commonly employed and, furthermore, to prevent discoloration of any of the parts of the container or the material contained therein by providing a sprinkler cap which is formed of a material unaffected by the contents of the bottle.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, with-

out departing from the spirit of the invention.

In the accompanying drawings the preferred form of the invention has been shown.

In said drawings:

Figure 1 is an enlarged section through a portion of a container having the present improvements combined therewith.

Fig. 2 is a plan view thereof, the stopper being removed.

Referring to the figures by characters of reference 1 designates a container preferably of glass and the neck 2 of which has the opening therein gradually restricted inwardly from the outer end of the neck, there being an inwardly extending endless rib or bulged portion 3 within the neck at a point between the ends thereof. The sprinkler cap 4 is preferably formed of cork and has a concentric recess 5 tapered inwardly and provided, in its bottom, with apertures 6. A stopper 7 preferably formed of glass is designed to fit snugly within the recess 5 and while in position therein the cork sprinkler cap can be forced downwardly into the neck 2 so as to become tightly wedged therein with the rib or bulged portion 3 pressing into the outer surface of the sprinkler cap so as to hold it in the neck and against accidental displacement relative thereto. When it is desired to remove a portion of the contents of the container, the stopper 7 is removed from the recess 5 whereupon the powder or other material in the container can be discharged through the apertures 6. When the stopper 7 is replaced the apertures 6 will be closed and the stopper will provide a neat finish to the container, the engaged portion of the sprinkler cap constituting a packing for holding the stopper against displacement.

Not only is a sprinkler cap such as herein described advantageous because it will not corrode or discolor the contents of the container, but also because it is practically invisible and gives the container the appearance of being entirely of glass.

What is claimed is:

The combination with a container having a neck extending therefrom formed with an

annular inwardly bulged portion, of a
sprinkler cap of cork or the like fitted
tightly within the neck and engaging and
retained by the bulged portion of the neck,
5 there being a downwardly tapered recess
within the sprinkler cap provided, at its bot-
tom, with outlet apertures, and a tapered
stopper slidably wedged within said recess
and bearing against the bottom of the re-
cess to close the outlet apertures, said stop-
per constituting means to compress the wall

of the sprinkler cap against the wall of the
neck and to embrace the inwardly bulged
portion of the neck of the container.

In testimony that I claim the foregoing 15
as my own, I have hereto affixed my sig-
nature in the presence of two witnesses.

AUGUST FREDERICK KAMMER.
